(57) **CLAIM**

The ornamental design for a battery charging box, as shown and described.

DESCRIPTION

FIG. 1 is a perspective view of a battery charging box showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear, right, bottom perspective view thereof.

FIG. 9 is a front, left perspective view thereof, shown in an open state.

FIG. 10 is a front, right perspective view thereof, shown in an open state; and,

FIG. 11 is an enlarged detail view of area 11 shown in FIG. 9.

The evenly-dashed broken lines in the drawings depict portions of the battery charging box that form no part of the claimed design.

The dot-dash broken lines depict the boundary of the enlarged views and form no part of the claimed design.
